UNITED STATES PATENT OFFICE.

ISTVÁN DUCSAY, OF CANONSBURG, PENNSYLVANIA.

DESIGN FOR A PICTURE-HANGER.

42,105.

Specification for Design.

Patented Jan. 23, 1912.

Application filed October 14, 1911. Serial No. 654,791. Term of patent 3½ years.

To all whom it may concern:

Be it known that I, ISTVÁN DUCSAY, a subject of the King of Hungary, residing at Canonsburg, in the county of Washington and State of Pennsylvania, have invented a certain new, original, and ornamental Design for a Picture-Hanger, of which the following is the specification, reference being had to the accompanying drawing, forming a part thereof.

The figure is a perspective view of the picture hanger, illustrating my new design.

I claim:

ISTVÁN DUCSAY.

Witnesses:

B. PRILCEZ,
W. J. GOWERN.
